SAND DRIER

Jose Raigosa, El Paso, Tex.

Application April 22, 1938, Serial No. 203,658

3 Claims. (Cl. 34—34)

My invention relates generally to means for drying sand, utilizing steam coils as the drying agent, and particularly to a sand drier especially constructed and adapted for installation and use at a building site, and preferably being portable, and an important object of my invention is to provide a simple, efficient, and relatively inexpensive arrangement of this character.

Other important objects of my invention will be apparent from a reading of the following description taken in connection with the drawings, wherein for purposes of illustration I have shown a preferred embodiment of my invention.

In the drawings:

Figure 1 is a general elevational view of the embodiment with the sprocket case broken away.

Figure 2 is an elevational view similar to Figure 1 but showing the exterior of the sprocket chain case.

Figure 3 is a top plan view of Figure 1.

Figure 4 is a bottom plan view of Figure 1.

Figure 5 is a longitudinal sectional view taken through Figure 1.

Figure 6 is a transverse vertical sectional view taken through Figure 5 approximately on the line 6—6 and looking toward the left in the direction of the arrows.

Referring in detail to the drawings, the numeral 5 generally designates an elongated rectangular casing formed by longitudinal side walls 6, 7 whose opposite ends are secured to the outer side of a flange of the angle iron corner supports 8, 9, the lower portions of the supports 8, 9 extending below the bottom of the casing and acting as legs to support the casing in spaced relation to the ground 10. The end walls 11 and 12 have inturned flanges 12, 13 which are secured to the inner face of the same flange of the angle irons as the ends of the longitudinal side members 6 and 7 are secured to. Longitudinal angle irons 14 and 15 are secured to the outer side of the longitudinal walls 6 and 7 adjacent the upper part thereof to lend rigidity to the structure and to facilitate handling when installing or removing the device from one site to another.

The lower edges of the end walls 11 and 12 are curvedly inturned as indicated by the numerals 16 and reach to the point 17 which constitutes one side of an opening in which the corresponding one of the rotors, respectively designated 18, 19, 20, turns, and through the sand is discharged from the bottom of the casing 5.

A partition acting as a bottom for the casing is generally designated 21 and comprises at least two transversely extending vertically projecting

triangular forms 22, the slanting walls of which terminate at their lower ends in curved portions 23, 24, the terminals of which define the sides of the openings in which the various rotors turn. The projections 22 separate the interior of the casing 5 into sand heating and drying compartments.

Each of the rotors 18, 19, 20 comprises a rotary shaft 25 which has one end journaled in a roller bearing 26 secured to the outside of the longitudinal wall 6 which the shaft traverses, and its opposite end journaled in a second roller bearing 27 similarly mounted on the outer side of the longitudinal casing wall 7. The last mentioned end of the shaft 25 has secured thereto a sprocket wheel 28 over which is trained a sprocket chain 29. Projecting radially from that portion of the shaft which lies between the side walls 6 and 7 and at equally circumferentially spaced distances are the diametrically opposed paddles 30, 31 which are elongated rectangular in shape and so disposed that when a pair of paddles is horizontally aligned with the edges of the openings in the bottom 21 of the casing, these openings will be closed so as to prevent the fall of sand from the respective compartment. The turning of the rotors has also the function of agitating the sand within the particular compartment and also the function of moving the sand to expose the same uniformly to the heat of the coils to be described. One of the rotors, preferably the central one designated 19 has its shaft provided with a projecting portion 32 which receives a manual crank 33, and a large sprocket wheel 24 is provided on this shaft and over which the sprocket chain 29 is trained, so that by turning the crank 33 the operator may determine the amount of sand discharged from the heating compartments or arrange for retention of the sand within all of the compartments by positioning the rotors with diametrically opposed pairs of paddles horizontally aligned with the edges of the openings in the bottom 21 of the casing. The sprocket wheels and the sprocket chain are enclosed in an elongated case 35 conforming generally in shape to the outline of the sprocket chain and this is secured in some suitable readily removable manner to the stationary portion of the roller bearings on the corresponding side of the casing.

The heating coils are arranged in groups within each of the heating compartments so as to heat the upper and intermediate and lower portions of these compartments, and in addition heating coils are provided beneath the bottom 21

of the casing so as to thoroughly and uniformly heat the bottom. Connection of a suitable source of steam supply may be made to the terminal 36 of the steam coil and from this point 5 the coil leads in a horizontal portion indicated by the numeral 37 across the left hand compartment and supportably over the top of the transversely spaced longitudinal support bars 38 and 39 which are connected at their opposite ends to 10 the upper part of the end walls 11 and 12 of the casing. Similar support rods 40 and 41 are disposed exactly beneath but spaced from the bars 38 and 39. From the end of the horizontal portion 37 extends downwardly a hairpin bend 42 15 which merges into a horizontal portion 43 which runs back across the casing under the horizontal portion 37 and approximately parallel thereto and from the far end of the portion 43 extends a downward hairpin bend 44 which merges into a 20 horizontal portion 45. The portion 43 rests on the support bar 39 while the horizontal portion 45 rests on the support bar 40. The portion 45 merges into a hairpin bend 46 which emerges into a horizontal portion 47 which rests on the 25 support bar 41 beyond which the portion 47 has a return hairpin bend 48 which merges into a horizontal portion 49 which terminates in a horizontally positioned hairpin bend 50 which leads into the lowermost horizontal portion 51 of an 30 arrangement of coil similar to that already described, so that there are two vertical tiers of convolutions in each of the end compartments of the casing. The similarly arranged vertical tiers of the central compartment are not perpendicularly arranged but the tiers are arranged at an acute angle to a middle tier which is arranged at a perpendicular angle. As shown in Figure 3 a portion 51 connects the top adjacent tiers of the left hand battery of convolutions with the 35 left hand one of the battery of convolutions in the central compartment, at the top thereof, while a coupling equipped portion 52 connects the lower part of the adjacent tiers of the right hand compartment and the extreme right tier of 40 the central compartment. The lowermost convolution of the right hand tier of the right hand compartment is connected by a coil portion 53 with a union 54 to which is connected a coil portion 55 which feeds the casing bottom heating 45 coil assembly which is generally designated 56. The coil arrangement 56 consists of a longitudinal coil portion 57 which has a discharge end 58; and a longitudinal coil portion 59 which includes the portion 55 which is connected to the union 54. The longitudinal coil portions 57 and 59 both have upset portions 60 and 61 which reach into the space between the upwardly projecting triangular portions 22 of the bottom of the casing, and other downwardly curved portions 62, 63 60 and 64 which are disposed below the respective rotors 18, 19, and 20 so that the rotors will clear the same in rotating. At the junction point of the portions 60, 62; 60, 63; 61, 63; 61, 64 are vertically spaced pairs of transversely arranged 65 pipes 65, 66 and 67, 68, respectively, which connect the longitudinal coil portions 57 and 59. Additional transverse pipes 69 and 70 at the right hand end of the bottom coil assembly 56 connect the corresponding ends of the longitudinal pipes 57 and 59 so as to produce a closed 70 circuit for the steam or other heating fluid. Other transverse tubes 71 and 72 connected between the longitudinal tubes 57 and 59 at the right hand end thereof are disposed inwardly of 75 the connection points 50 and 55. By means of

the arrangements described, steam or other heating fluid being introduced through the connection 58, the heating fluid will pass first through the bottom heating assembly 56 and then upwardly through the connection 53 to the right hand battery of coils in the right hand heating compartment, thence to the central heating compartment, and then from the top of the coil assembly therein to the top of the coil assembly within the left hand heating compartment, thereby evenly and uniformly heating the sand which may be introduced into each or any of the compartments and drying the same for discharge in a properly dried condition from the openings in the bottom of the casing by operation of the rotors through manipulation of the crank handle 33.

Although I have shown and described herein a preferred embodiment of my invention, it is to be definitely understood that I do not desire to limit the application of the invention thereto, and any change or changes may be made in the structure and arrangement of parts, within the spirit of the invention and the scope of the subjoined claims.

Having described the invention, what is claimed as new is:

1. A sand drier comprising a substantially rectangular elongated casing formed in its bottom with transverse sand discharging openings, said discharging openings being spaced from each other and from the ends of the casing, a hollow inverted V-shaped partition between adjacent ones of said discharging openings, said partition being open at its bottom, said partitions reaching up into the casing and across the same so as to divide the interior of the casing into sand drying compartments, gate means disposed in each of said discharging openings for opening and closing the same, and heating means consisting of a web of pipes disposed along and beneath a substantial area of the bottom of the casing, elevated portions of said heating pipes extending up into the interior of said hollow partitions through the open bottoms thereof, other portions of said heating pipes extending at a level below the opposite end portions of said discharging openings in heating relation to the gates.

2. A sand drier comprising a substantially rectangular elongated casing formed in its bottom with transverse sand discharging openings, said discharging openings being spaced from each other and from the ends of the casing, a hollow inverted V-shaped partition between adjacent ones of said discharging openings, said partition being open at its bottom, said partitions reaching up into the casing and across the same so as to divide the interior of the casing into sand drying compartments, gate means disposed in each of said discharging openings for opening and closing the same, and heating means disposed along and beneath a substantial area of the bottom of the casing, elevated portions of said heating means extending up into the interior of said hollow partitions through the open bottoms thereof, other portions of said heating means extending along the sides and across the ends of said discharging openings.

3. A sand drier comprising a substantially rectangular elongated casing formed in its bottom with transverse sand discharging openings, said discharging openings being spaced from each other and from the ends of the casing, a hollow inverted V-shaped partition between adjacent

ones of said discharging openings, said partition being open at its bottom, said partitions reaching up into the casing and across the same so as to divide the interior of the casing into sand drying compartments, rotary gate means disposed in each of said discharging openings on an axis transverse with respect to the casing for opening and closing said discharging openings, and heating means disposed along and beneath a substantial area of the bottom of the

casing, elevated portions of said heating means extending up into the interior of said hollow partitions through the open bottoms thereof, depressed portions of said heating means located between said elevated portions of the heating means being arranged beneath each of said gate means, and common operating means for operating said rotary members together. 5

JOSE RAIGOSA. 10
